ELEVATOR DOOR

Filed Dec. 3, 1926

UNITED STATES PATENT OFFICE.

ROBERT S. PEELLE, OF NEW YORK, N. Y., ASSIGNOR TO THE PEELLE COMPANY, OF BROOKLYN, NEW YORK, A CORPORATION OF NEW YORK.

ELEVATOR DOOR.

Application filed December 3, 1926. Serial No. 152,361.

My invention relates to elevator doors, and more particularly to fire retardant doors having metal sheathed wooden panels.

In doors of the type to which my invention relates, it has long been the practice to apply a metal sheathing to the wooden core of a door with the sole object of affording a non-combustible surface to the planks forming the core of the panel. This sheathing material was composed of small thin sheets of tinned or galvanized iron, each sheet being secured to other sheets about each edge thereof by means of a special form of lap joint known as an "underwriters' joint," each sheet or plate being nailed adjacent each seam to the wood of the panel.

While wooden panels sheathed in the manner above described are highly effective in providing fire retardant properties in the door, the number and arrangement of seams is such that the metal sheathing imparts no strength to the door structure in its entirety, acting solely as a fire retardant.

In the event of the subjection of an elevator door to extremely high temperatures, the wooden core of a door panel frequently is so charred as to offer little or no support to the metal sheathing, in which case there is a tendency of the sheathing to buckle or become distorted with the possibility of the opening of seams and a partial destruction of the non-inflammable properties of the door in its entirety as a result of the passage of flame and combustion supporting gases to the wooden core. This condition is further exaggerated by the tendency of the metal frame of such doors to warp under high temperature conditions, a metal sheathed panel as heretofore used when the wooden core is charred, offering no resistance to such warping of the frame.

In addition to the undesirable characteristics above referred to, the large number of separate sheets of which the metal sheathing is composed, and the arrangement of the seams connecting such sheets, is such that the sheathing operation must be done entirely by hand, thus making the production of the panels of such doors expensive, the workmen being required in large doors to form approximately 400 seams in a door having a height of between 4 and 5 feet and a width of 20 feet. Furthermore, the time required to form these

seams is so great that light metal stock is used to reduce the labor, and time interval, required in the production of the panel.

With the above conditions in mind, I have produced a metal sheathed wooden core door in which the sheathing is not only of a thickness to possess considerable inherent rigidity, but in which the seams are so arranged as to afford braces extending from the top bar to the bottom bar of the angle metal frame usually employed with such doors, which not only resist buckling or distortion of the sheathing in the event of the charring of the core of the panel in the event of fire, but warping of the top and the bottom bars of the frame. Furthermore, these seams, by reason of the thickness and the bulk of the metal therein, serve to reinforce or brace the top and bottom bars of the frame at all times while the door is in use, and thus impart additional strength and rigidity to the door panel as a whole.

In the production of doors embodying the invention, with a door of 4 or 5 feet in height and 20 feet in width, the number of seams to be formed would be about 16 as compared with 400 in the old type of metal sheathed door, and the arrangement of these seams is such that the final operation, if desired, may be done by machinery.

Hence in a door embodying the invention, not only are the fire retardant properties enhanced by the thickness of the metal sheathing, but the rigidity inherent to metal of increased thickness, as well as the arrangement of the seams, serve as a reinforcement not only to the panel, but to the top and bottom bars of the frame of the door. Furthermore, the cost of producing such doors is very much less than the old type of metal sheathed wooden core panels, because of the very much lessened amount of labor required both as to the driving of nails and as to the forming of the seams, even though these seams be closed by hand and not by a machine.

The invention consists primarily in an elevator door embodying therein a metal frame having a top and a bottom bar, and a panel, secured to, and closing the opening within said frame, said panel being formed of a wooden core, and a cover sheathing consisting of a plurality of strips of sheet metal extending vertically throughout the entire

height of the panel, the edges of adjoining sheets being connected by a lapped and folded joint, whereby the superimposed plies of the metal of said joints form continuous 5 braces extending between the upper and lower bars of said frame, and the sheathing has but few joints; and in such other novel features of construction and combination of parts, as are hereinafter set forth and described, and more particularly pointed out in the claims hereto appended.

Referring to the drawings,

Fig. 1 is a condensed elevation of a door embodying the invention with portions of 15 the sheathing broken away;

Fig. 2 is a section on the line 2—2 of Fig. 1 upon an enlarged scale;

Fig. 3 is an edge view of a portion of the 20 panel; and

Fig. 4 is a view in perspective of one corner thereof.

Like letters refer to like parts throughout the several views.

In the embodiment of the invention shown 25 in the drawings, the metal frame of the door is shown as being of a continuous angle metal construction which is old and well known in this art, said frame having top and bottom bars *a* and *b*, and opposite side bars *c* and *d*, 30 one flange of each of these bars being directed inwardly of the frame.

Closing the opening within this frame is a metal sheathed wooden panel which is secured to the frame in the usual manner, as 35 by being bolted to the inwardly directed flange of the bars of the frame. All portions of the door structure, excepting the frame and the panel, are omitted from the drawings, and will not be described as such 40 are not necessary to an understanding of the invention and may take a variety of forms old and well known in the elevator door art.

The panel above referred to has a core *e* 45 of wooden planks, the thickness of this core varying with doors of different dimensions or for different conditions of use. The metal sheathing consists of a plurality of continuous vertically extending strips of sheet metal, which may be tinned or galvanized 50 or otherwise surfaced to prevent oxidation of the iron of the sheet, which strips extend continuously from adjacent the top rail *a* to adjacent the bottom rail *b*, or throughout 55 the entire height of the panel. While preferably tinned or galvanized iron sheets are employed, other materials may be used in these strips, although coated iron sheets are preferable, not only because of their cheapness but because of the strength inherent 60 thereto.

Two adjacent strips are shown at *f* and 65 *g*, it being understood that the width and number of such sheets may be varied in doors of different widths, as may the gauge of the sheet metal stock.

Highly satisfactory results have been secured with 25 to 26 gauge sheet metal, which material is of sufficient thickness to materially stiffen the sheathing at all points of the panel while permitting bending adjacent the 70 edges thereof in forming the lapped and folded joints known as "underwriters' joints".

The width of the sheets used varies from 12 to 36 inches, according to the width of 75 the door. With narrow doors, 8 to 10 feet in width, narrower strips are used, while with wider doors, wider strips are used. The width of the strip as well as the gauge of the sheet metal stock is determined by the width 80 of the door and its conditions of use. With wider doors, the frame structure is much heavier and is more heavily reinforced than with narrower doors, so that under ordinary conditions of use the bracing of the frame by 85 means of the sheathing, as to the number of joints, need not be increased as compared with narrower doors, particularly if heavier stock be used. On the other hand, if the wide doors are to be subjected to heavy sur- 90 face, then narrower strips may be used so as to increase the number of braces formed by said joints.

In connecting adjoining strips, one edge 95 of a strip, as *f*, is folded upon the strip, as indicated at *f'*, and the contiguous edge of the adjoining strip *g* is bent or folded at an angle upwardly as at *g'*, downwardly as at *g''* and at right angles as at *g'''* so as to form a tongue adapted to pass under and interlock 100 with the fold *f'* of the adjoining strip *f*. The fold *f'* and the folds *g'-g''-g'''*, extend along the entire edge of the strips *f* and *g* respectively. The opposite edge of the strip *f* is formed in the same manner as the edge 105 of the strip *g* heretofore described, and the opposite edge of the strip *g* is provided with a fold like the fold *f'*. These folds may take up three or four inches from the width of the strip, the joint in its entirety being approximately an inch in width.

In forming the joint, the tongue *g'''* is slipped within the fold *f'*, and nails are driven through the four plies of sheathing material into the core *e*, the fold *f'* first having been closed upon the tongue *g'''*.

The positioning of the strips is hand labor, as well as the driving of the nails, but the formation of the folds may be by means of machinery, as may be the closing of the folds. 110 When the strips are thus nailed to the core, the folds *g'-g''* are closed upon the strip *g* and above the fold *f'*, and the tongue *g'''*. If desired, this also may be machine work.

When the lapped and folded joint is completed, there will be a brace having six laminae of the metal stock of the sheathing extending from the top bar *a* to the bottom bar *b* of the frame, which brace will be of approximately one-eighth of an inch in thickness, 115 120 125 130

and, with its laminated structure, will afford a very effective brace between both bars *a* and *b*.

The above figures apply to wide doors, 5 there being about eight such braces at each side of the panel of a door twenty feet in width. If stock of less than thirty-six inches in width be used, of course the number of such braces will be increased. With narrower doors, which are lighter in construction throughout, narrower strips are used so that with an eight foot door, the number of brace forming joints on each side of the panel might be as high as twelve, with twelve inch 15 stock, or as low as seven if eighteen inch stock were used. Irrespective of the width of the door, there will be present in the door structure a sequence of equally spaced reinforcing laminated brace bars forming an integral 20 part of the sheathing and serving to resist stresses applied to the top bar structure.

After the sheathing strips have been applied to the opposite faces of the core *e* in the manner described, the edges of the fabricated 25 sheathing are bent, or formed, over the edges of the core *e*, the sheathing on one side laps over the other side, if desired, and these edges are then nailed to the core. At the corners of the panel, the material of the 30 strip is formed and bent as indicated in Fig. 4, so as to avoid bulkiness at this point. This utilization of the sheathing for protecting the edges of the panel is desirable as supplementing the protection afforded the edge of the 35 panel, by the angle metal frame, in the event of fire.

It is preferable, when making the joints at one side of the panel, to so locate them that the joints upon the other side of the panel 40 will be staggered in relation thereto, or alternated therewith, thus decreasing the space between the braces afforded by the joints in their supporting action in relation to the top and bottom bars of the frame.

In a door embodying the invention, the 45 only joints in the sheathing will be those forming the braces extending from the top to the bottom bar of the frame, and the continuity and bulk of these joints and their few number, will increase the strength of the sheathing rather than be weak spots in the event of the subjection of the door to high temperature. In addition to reinforcing the frame of the door, the brace forming 50 joints will resist distortion of the sheathing upon opposite sides of the door, and reduce to a minimum likelihood of the opening of the seams in the event of fire due to such distortion.

With a construction as herein described, 60 the strength of the door in its entirety is materially increased, its fire retardant properties are enhanced, and the cost of production is reduced in part by the reduction of the 65 number of seams or joints and in part by the

employment of a construction which permits the utilization of machines in lieu of hand labor. In referring to the use of machines, it will be obvious that a special press may be used for closing the fold *f'* upon the tongue *g'*, and that the bending or folding of the parts *g'* and *g''* in the manner described may be by means of an ordinary roller which will entail merely the passing of the panel in its entirety in operative relation to said roller. 70 If, however, it is not desired to resort to machine work, these steps may be done by hand much more economically than the formation of the joints of the doors heretofore used.

I have herein shown and described the use 80 of the ordinary "fire underwriters' joint" as a securing means between adjacent strips, but it is obvious that any other type of lap and fold joint may be used. The "underwriters' joint" has been used merely because this is a 85 form of joint which has been tested and approved as coming within the requirements of the National Board of Fire Underwriters.

It is not my intention, therefore, to limit the invention to the use of the particular 90 form of joint shown in the accompanying drawings, the number of such joints, or any particular thickness of the metal stock of the sheathing, since obviously such may be varied without departing from the spirit 95 and scope of the invention. The essential characteristic of the invention is a construction in which the metal sheathing is formed of strips extending vertically of the door, and the adjoining strips are secured together 100 by a lap and folded joint, thus incorporating in the door structure, braces extending from the top, to the bottom, bar of the frame of the door, which braces are incorporated in, and form an integral part of, the sheathing 105 structure so as to not only reinforce said bars, but also the sheathing in its entirety.

Having described the invention, what I 110 claim as new and desire to have protected by Letters Patent, is—

1. An elevator door embodying therein a metal frame having a top and a bottom bar, and a panel, secured to, and closing the opening within said frame, said panel being formed of a wooden core, and a cover sheathing consisting of a plurality of strips of sheet metal extending vertically throughout the entire height of the panel, the edges of adjoining sheets being connected by a lapped and folded joint, whereby the superimposed plies 115 of the metal of said joints form continuous braces extending between the upper and lower bars of said frame, and the sheathing has but few joints.

2. An elevator door embodying therein a metal frame having a top and a bottom bar, and a panel, secured to, and closing the opening within said frame, said panel being formed of a wooden core, a cover sheathing 120 consisting of a plurality of strips of sheet 125 metal extending vertically throughout the entire height of the panel, the edges of adjoining sheets being connected by a lapped and folded joint, whereby the superimposed plies of the metal of said joints form continuous braces extending between the upper and lower bars of said frame, and the sheathing has but few joints.

- metal extending vertically throughout the entire height of the panel, the edges of adjoining sheets being connected by a lapped and folded joint, whereby the superimposed plies of the metal of said joints form continuous braces extending between the upper and lower bars of said frame, and the sheathing has but few joints, the edges of said cover sheathing being formed over the edges of said core, and means securing the formed portions of said sheathing to the edges of said core, the joints of the sheathing upon the opposite sides of said core being staggered with relation to each other.
- 5 10 15 20 25 30 35 40 45 50 55 60 65 70 75 80 85 90 95 100 105
3. An elevator door embodying therein a metal frame having a top and a bottom bar, and a panel, secured to, and closing the opening within said frame, said panel being formed of a wooden core, a cover sheathing consisting of a plurality of strips of sheet metal extending vertically throughout the entire height of the panel, the edges of adjoining sheets being connected by a lapped and folded joint, whereby the superimposed plies of the metal of said joints form continuous braces extending between the upper and lower bars of said frame, and the sheathing has but few joints, and securing means passing through portions of said superimposed plies and co-operating with said wooden core.
4. An elevator door embodying therein a metal frame having a top and a bottom bar, and a panel, secured to, and closing the opening within said frame, said panel being formed of a wooden core, and a cover sheathing consisting of a plurality of strips of sheet metal extending vertically throughout the entire height of the panel, the edges of adjoining sheets being connected by a lapped and folded joint, whereby the superimposed plies of the metal of said joints form continuous braces extending between the upper and lower bars of said frame, and the sheathing has but few joints, the joints of the sheathing upon the opposite sides of said core being staggered with relation to each other.
5. An elevator door embodying therein a metal frame having a top and a bottom bar, and a panel, secured to, and closing the opening within said frame, said panel being formed of a wooden core, a cover sheathing consisting of a plurality of strips of sheet metal extending vertically throughout the entire height of the panel, the edges of adjoining sheets being connected by a lapped and folded joint, whereby the superimposed plies of the metal of said joints form continuous braces extending between the upper and lower bars of said frame, and the sheathing has but few joints, securing means passing through portions of said superimposed plies and co-operating with said wooden core, the edges of said cover sheathing being formed over the edges of said core, and means securing the formed portions of said sheathing to the edges of said core.

6. An elevator door embodying therein a metal frame having a top and a bottom bar, and a panel, secured to, and closing the opening within said frame, said panel being formed of a wooden core, a cover sheathing consisting of a plurality of strips of sheet metal extending vertically throughout the entire height of the panel, the edges of adjoining sheets being connected by a lapped and folded joint, whereby the superimposed plies of the metal of said joints form continuous braces extending between the upper and lower bars of said frame, and the sheathing has but few joints, securing means passing through portions of said superimposed plies and co-operating with relation to each other.

65 70 75 80 85 90 95 100 105

6. An elevator door embodying therein a metal frame having a top and a bottom bar, and a panel, secured to, and closing the opening within said frame, said panel being formed of a wooden core, a cover sheathing consisting of a plurality of strips of sheet metal extending vertically throughout the entire height of the panel, the edges of adjoining sheets being connected by a lapped and folded joint, whereby the superimposed plies of the metal of said joints form continuous braces extending between the upper and lower bars of said frame, and the sheathing has but few joints, securing means passing through portions of said superimposed plies and co-operating with said wooden core, the edges of said cover sheathing being formed over the edges of said core, and means securing the formed portions of said sheathing to the edges of said core.

7. An elevator door embodying therein a metal frame having a top and a bottom bar, and a panel, secured to, and closing the opening within said frame, said panel being formed of a wooden core, a cover sheathing consisting of a plurality of strips of sheet metal extending vertically throughout the entire height of the panel, the edges of adjoining sheets being connected by a lapped and folded joint, whereby the superimposed plies of the metal of said joints form continuous braces extending between the upper and lower bars of said frame, and the sheathing has but few joints, securing means passing through portions of said superimposed plies and co-operating with said wooden core, the edges of said cover sheathing being formed over the edges of said core, and means securing the formed portions of said sheathing to the edges of said core, the joints of the sheathing upon the opposite sides of said core being staggered with relation to each other.

In witness whereof I have hereunto affixed my signature, this 20th day of November, 1926.

ROBERT S. PEELE.
